CLAIM

The ornamental design for an endotracheal tube as shown and described.

DESCRIPTION

FIG. 1 is a top, front perspective view of an endotracheal tube showing my new design;

FIG. 2 is a bottom, front perspective view thereof;

FIG. 3 is a left view thereof;

FIG. 4 is a right view thereof;

FIG. 5 is a rear view thereof;

FIG. 6 is a front view thereof;

FIG. 7 is a top view thereof; and,

FIG. 8 is a bottom view thereof.

The broken lines shown in FIGS. 1–8 illustrate portions of the endotracheal tube that form no part of the claimed design.

1 Claim, 5 Drawing Sheets
